ABSTRACT

Furnace assembly providing a working volume the pressure in which may range from 10^{-5} torr to 135 atmospheres. Controlled temperatures up to 3,000°C are attainable. A crystal-pulling rod and a crucible-supporting rod extend into the furnace. The crystal-pulling rod is rotated and driven translationally through an extended excursion in a slow crystal-pulling mode and relatively fast positioning mode; while the crucible support rod is rotated and driven translationally through a relatively short excursion in a crucible positioning mode. The main furnace housing is lifted up and swung away to permit ready access to the crucible holding zone for interchange of rf coils and crucible holders as well as for easy safe removal of large crystals suspended from the pulling rod. Means are provided continuously to indicate the precise position of the crystal-pulling rod, to monitor the operation within the furnace by TV, and to control the operations within the furnace from a remote location.

PRESSURE-AND TEMPERATURE-CONTROLLED
APPARATUS FOR LARGE-SCALE PRODUCTION
OF CRYSTALS BY THE CZOCHRALSKI
TECHNIQUE

This invention relates to an apparatus for growing crystals and more particularly to an apparatus for growing crystals on a large scale by the Czochralski technique under controlled atmospheric pressures from 10^{-5} torr to 135 atmospheres and at temperatures up to 3,000°C.

An apparatus suitable for growing many different types of crystals by the Czochralski technique is required to be able to furnish many different controlled conditions. For example, the growing of crystals of a III-V intermetallic compound may require that a very high pressure be maintained around the growing crystal area to control the vaporization of a volatile component such as arsenic or phosphorus in forming an intermetallic arsenide or phosphide. In other crystal growing processes it may be necessary to supply a moderate to high vacuum. In all cases, however, the working zone within the apparatus must be evacuable to permit control of the zone atmosphere, whether it is pressurized or evacuated during crystal growth. Such a crystal growing apparatus should be capable of growing crystals of oxides, salts, metals, elemental and intermetallic compound semiconductors including the phosphides, arsenides, tellurides, selenides and sulfides and any other inorganic element, compound or mixtures thereof.

With the ever-increasing demand for single crystal raw stock for making semi-conductor devices, light-emitting diodes, etc., there has arisen the need for a crystal growing apparatus which is safe, reliable and easy to operate for the production of crystals on a large, commercial scale. One of the most widely accepted techniques for forming single crystals is the vertical pulling or Czochralski technique in which a seed crystal is contacted with the surface of a molten reservoir of the material to be formed into a crystal and then gradually pulled upwardly with rotation.

In a copending application Ser. No. 46,096 filed June 15, 1970, in our names and assigned to the same assignee as the present application and now U.S. Pat. No. 3,639,718, we have described and claimed a multipurpose furnace for experimental purposes for growing crystals by either the Czochralski, Bridgman-Stockbarger, or floating-zone techniques; for forming intermetallic compounds within controlled atmospheres such as by the methods described in U.S. Pat. No. 3,704,093 and Ser. No. 169,315 filed in the names of Wilson P. Menashi, Joseph F. Wenckus and Roger A. Castonguay; and for forming doped crystals of uniform composition. All of the above-identified applications have been assigned to the same assignee as the present case. Inasmuch as the furnace of Ser. No. 46,096 as a versatile research tool must provide for a wide variety of operational conditions, it is not suitable for growing large-scale crystals by a single technique on a commercial basis. In addition to providing for a wide range of operational pressures and temperatures, a crystal growing furnace suitable for growing large crystals on a commercial basis should provide easy access for the installation of various sizes and types of crucibles and for the removal of large crystals, fail-safe operational features and complete remote control. The

crystal growing apparatus of this invention, hereinafter referred to as a "furnace" meets all of these requirements as will be evident from the following detailed description.

5 It is therefore a primary object of this invention to provide a crystal growing furnace for producing crystals on a commercial scale by the Czochralski technique which may be used over a pressure range from as low as 10^{-5} torr to as high as 135 atmospheres and at 10 temperatures up to 3,000°C. It is another object of this invention to provide apparatus of the character described which offers rapid, easy and safe access to the working zone, which makes possible the growing of a crystal over a wide size range, and which permits the 15 use of a wide variation in crucible sizes and configurations to supply the molten crystal-forming material. It is yet another object of this invention to provide such apparatus which is suitable for operation by remote control and remote observation, and which has built 20 into it safety features which make the apparatus reliable to use under any extreme high vacuum or pressure and temperatures desired. It is yet another object of this invention to provide such an apparatus which permits rapid height adjustments of the upper or crystal-pulling rod before, during, and after the crystal growing 25 operation and which provides means for continuous monitoring of the position of the crystal-pulling rod. Other objects of the invention will in part be obvious 30 and will in part be apparent hereinafter.

The invention accordingly comprises the features of construction, combinations of elements, and arrangements of parts which will be exemplified in the constructions hereinafter set forth, and the scope of the invention will be indicated in the claims.

35 For a fuller understanding of the nature and objects of the invention, reference should be had to the following detailed description taken in connection with the accompanying drawings in which

40 FIG. 1 is a perspective view of the apparatus of this invention showing the furnace assembly in operational condition, the power supply and the operational console;

45 FIG. 2 is a front view of the furnace assembly of FIG. 1 illustrating the main furnace housing raised and swung away for access to the working zone;

FIGS. 3, 4 and 5 are side, top and end views, respectively, of the crystal-pulling rod driving mechanism;

50 FIG. 6 is a top plan view of the furnace assembly;

FIG. 7 is a side elevational view of the furnace assembly;

FIGS. 8 and 9 are cross sections through the furnace chamber lift support structure taken along lines 8-8 and 9-9, respectively, of FIG. 7;

55 FIG. 10 is a side elevational view of the crucible support mechanism, vacuum system, pressure-control system and hydraulic system of the furnace assembly

FIG. 11 is a front elevational view of the furnace;

60 FIG. 12 is a fragmentary detail of a warning device mounted on the furnace housing to prevent opening of the furnace when it is pressurized;

FIG. 13 is a front elevational view of the crucible support mechanism, vacuum system, pressure-control system and hydraulic system of the furnace assembly;

65 FIG. 14 is a vertical cross section of the furnace showing one window in cross section and one embodiment of the crucible holder;

FIG. 15 is a vertical cross section of the lower portion of the furnace showing another embodiment of the crucible heater, of the crucible holder and the bearing and sealing assembly for the crucible support rod;

FIG. 16 is a perspective view of the rotational and translational driving mechanisms for the crystal-pulling rod;

FIG. 17 is a detailed cross sectional view of the rotational and translational shaft driving mechanisms associated with the crystal-pulling rod;

FIG. 18 is a cross sectional view of the mechanism of FIG. 17 taken along line 18-18 of that figure;

FIG. 19 is a detail of the upper end of the upper rod showing the means for introducing and withdrawing a cooling liquid;

FIG. 20 is a diagram showing the flow of a liquid coolant around the furnace assembly;

FIG. 21 illustrates diagrammatically the mechanism for continuous read-out of the positions of the load-bearing rods;

FIG. 22 illustrates diagrammatically the temperature control system; and

FIG. 23 illustrates diagrammatically the mechanism for choosing between the slow and fast driving modes for the crystal pulling head as well as other driving mechanism controls.

The crystal growing apparatus of this invention includes a pressure-sealed, water-cooled furnace assembly comprising a main furnace housing and a furnace base, an upper crystal-pulling rod with translational and rotational drive mechanisms, a lower crucible support rod with translational and rotational drive mechanism, means to raise and rotate the main furnace housing to provide ready access to the working zone and to remove large crystals, and fail-safe control means to prevent opening of the furnace while it is pressurized. The translational driving mechanism associated with the crystal-pulling rod may be alternatively operated in a slow, crystal-growing mode, or in a fast, rapid-positioning mode. Means are also supplied to monitor the temperature of the crystal growing area, to interchange the crystal holding means, to cool the upper pulling rod within the furnace and to determine precisely the position of the pulling rod. The main furnace housing has a viewing post system suitable for accommodating a television camera for remote monitoring and controlling and for supplying a source of light when required.

The apparatus of this invention, along with a power supply and control console, is illustrated in a perspective view of FIG. 1. It will be seen to comprise a main furnace assembly 10, a power supply 11 and an operational console 12, the furnace being separated physically from the power supply and the operational console by a suitable barrier such as a wall 13. Although the furnace assembly has been designed to meet the requirements of Section VIII of the ASME Pressure Vessel Codes, it is always desirable to locate such apparatus which is maintained at a high pressure remote from any operating personnel. As will be apparent in the following description the apparatus of this invention may be controlled and monitored from a remote location.

The furnace assembly is shown generally in outline form in FIGS. 1 and 2, FIG. 1 showing the furnace closed for operation and FIG. 2 showing it open for removal of a crystal 14. The furnace assembly comprises the main furnace housing 15, the furnace base 16 pres-

sure-sealable to the housing by means of a closure ring 17, hydraulically actuated furnace housing lifting means 18, the pulling rod driving mechanism 19 and the crucible support driving mechanism 20. The main furnace housing 15 has two pressure-sealed viewing ports 21 and 22, one of which may have a TV camera 23 associated with it and positioned on a TV camera support 24, the other of which may have a light source, not shown, mounted so as to provide illumination of the working zone within the furnace during those periods of operation when the zone is not self-illuminated. With the TV camera in position as shown in FIG. 1, the operator may view the crystal growing process on TV screen 25 located on operational console 12.

15 The crucible assembly 26, including a heater 27, is mounted in furnace base 16 which in turn is set in an annular furnace support 28. Power for heating the crystal growing area is supplied by way of an inlet conduit 30. The pressure maintained within the furnace is monitored through a pressure or vacuum gauge 31 communicating with the working zone within the furnace housing. For remote monitoring a second pressure gauge 32 is located on console 12.

25 The crystal-pulling rod and crucible-support rod used within the furnace and their associated driving mechanisms are illustrated very generally in FIGS. 1 and 2 and will be described in detail with regard to FIGS. 16-19 presented below. The crystal-pulling rod mechanism is generally indicated at 36 and the crucible-support rod mechanism at 37. The driving mechanism 19 for the crystal-pulling mechanism 36 is mounted directly on the main furnace housing and is raised and swung around with it by the furnace housing lifting means 18. This furnace assembly is mounted on a base 30 plate 40 and the base plate is supported on frame structure 41 which may be rendered movable by the engagement of casters 42. The hydraulic mechanism 43 for operating the furnace housing lifting means is positioned on frame 41 under base 40. As will be described below in conjunction with FIGS. 10 and 13, the driving mechanism for the crucible-support rod, as well as connections and controls for gas and cooling water lines 45, are located within the bottom portion of frame 40. Cooling coils, generally shown at 44 and described in detail with reference to FIG. 20, are provided for circulating a liquid coolant around the furnace assembly. Various other numbered components in FIGS. 1 and 2 will be identified below.

35 FIGS. 3 through 13 illustrate the external features of the apparatus in detail and reference should be had to these drawings, in which like numerals identify like components, in the following description. FIGS. 3, 4 and 5 are side, top and end views of the drive trains for the crystal-pulling rod driving mechanisms; FIG. 6 is a top plan view of the furnace above base 40; FIGS. 7 and 10 together form a complete side view of the entire furnace; and FIGS. 11 and 13 together form a complete end view of the entire furnace. FIGS. 8, 9 and 12 show fragmentary details of external features.

40 In forming a crystal by the Czochralski technique, a seed is affixed to a crystal-pulling rod and contacted with the surface of a molten pool of the material from which the crystal is to be formed. The seed with the crystal forming thereon is then slowly pulled upwardly while being rotated. Thus the driving mechanism 19 associated with the crystal-pulling rod 36 (FIGS. 1 and 2) must be capable of imparting translational as well as ro-

tational motion to the pulling rod. Since the speed at which the rod is moved in the translational mode is very slow (e.g., $\frac{1}{4}$ to 2 inches per hour) it is desirable to provide means for moving the pulling rod at a much faster speed for gross positioning operations. Hence the furnace of this invention has means to impart translational motion to the pulling head at a slow variable crystal-growing speed (crystal-growing mode) and at a fast positioning speed (positioning mode). The drive trains for the two modes of translational motion and for rotational motion are shown in detail in FIGS. 3-6.

These two translational operational modes are attained through the use of a single dc shunt-wound, variable control speed motor 51. This motor is affixed to a pulling rod drive support assembly comprising a vertical support member 52 which is mounted on a right-angle mounting block 53. The right-angle mounting block is in turn affixed to a primary mounting plate 54 which in turn is attached to the pulling rod drive housing 55 mounted on top of the main furnace housing 15. The rotational drive motor 58 is likewise rigidly affixed to the pulling rod drive housing 55 through a support plate 59. (FIG. 4).

The drive trains for the crystal-pulling and positioning operating modes of translational motion may be explained with particular reference to FIG. 3. The drive train used for the slow crystal-pulling mode comprises motor 51, a shaft (not shown) within shaft (housing 65, a low speed drive mechanism including a suitable gear head 66 mounted on vertical support member 52, slow speed drive 67, a slow-speed drive shaft 68 engagable, through an electromagnetic clutch 69, with a low-speed gear shaft 70 of low-speed gear 71, a T-gear 72 (i.e., a right angle drive) affixed to primary mounting plate 54 through a support 73 (FIG. 4), T-gear shaft 74, slip clutch 75 and pulling rod drive shaft 76, described in detail with reference to FIGS. 16-19.

The drive train used for the fast positioning mode comprises motor 51, high-speed motor shaft 80, pulley 81 mounted thereon, belt 82, driving wheel 83 mounted on shaft 84 which is supported in a bearing block 85 (affixed to primary mounting plate 54), high-speed gear shaft 86 of the high-speed gear 87 of T-gear 72 engagable with shaft 84 through an electromagnetic clutch 88, T-gear 72, T-gear shaft 74, slip clutch 75 and pulling rod drive shaft 76.

In the slow, crystal-growing operational mode, electro-magnetic clutch 88 is uncoupled and that portion of the high-speed drive comprising motor shaft 80, belt 82, wheel 83 and shaft 84 idles. In the fast, positioning mode, electromagnetic clutch 69 is uncoupled. The control mechanism associated with these drive trains, which includes an automatic shut-off system, is described in detail with reference to FIG. 23.

As will be seen in FIGS. 4 and 6, the shaft 60 of rotational drive motor 58 is coupled through coupling 61 to the rotational drive shaft 62 of the pulling rod drive assembly which is described in detail with reference to FIGS. 16-19.

As will be seen more clearly in FIGS. 7 and 11, the entire driving mechanism 19 associated with the crystal-pulling rod is rigidly mounted to the top of the main furnace housing 15. Therefore, when the main furnace housing is raised and swung around, the driving mechanism is likewise raised and swung around. The mechanism for moving the furnace housing is illustrated in detail in FIGS. 7-10. A hydraulically driven lifting shaft

96 is axially movable within an upper heavy duty bearing system 97 and lower heavy duty bearing system 98, the housings for these bearing systems being preferably cast integral with the T-shaped vertical bearing support 99, having a release notch 100 in its upper end corresponding to the height to which the main furnace housing must be raised before it may be swung around. The vertical bearing support is mounted through a horizontal plate 101 to base plate 40. The main furnace housing is rigidly affixed to lifting shaft 96 through an upper arm 102 bolted to an upper two-piece collar 103 and through a lower arm 104 bolted to a lower two-piece collar 105 having a right-angled extension arm 106. The lower collar has a key-way piece 107 affixed to it and adapted to engage the inside vertically oriented edge 108 of the vertical bearing support 99 along its length (see FIG. 8) until it reaches release notch 100 where such engagement is broken. Thus when the furnace housing, along with the crystal-pulling rod driving mechanism, has been raised to this release position (FIG. 9) it may be swung around to completely expose the working zone in which the crucible assembly 26 is located as shown in FIG. 2. When the main furnace housing is in the position illustrated in FIG. 2, it is easy to remove the crystal 14 and to interchange crucibles and heaters and perform any other operations in the furnace working zone.

In order to prevent any vibration of the furnace during crystal pulling, a vertical support arm 109 is affixed to primary mounting plate 54 and positioned to engage the top of lifting shaft 96 to mechanically link and stabilize the driving mechanism 19 and lifting mechanism 18.

The furnace chamber closure means 17 for sealing the main furnace housing 15 to furnace base 16 comprises two internally grooved semi-circular rings 120 and 121 having enlarged outwardly flanged and upwardly extending ends, such as the two ends 122 and 123 shown in FIG. 11 for one side of semi-circular rings 120 and 121, respectively. Gaskets, such as 125 and 126 shown in FIG. 11 are located on the inner surfaces of the ends of the rings and are positioned to form a single gasket assembly. Mechanical loading to resist internal pressure is accomplished through the use of two long bolts 130 and 131 which pass through central bushings such as bushing 132 in FIG. 11.

With the unloosening of bolts 130 and 131, the semi-circular rings may be slipped off the flanges of the furnace base and housing (see FIG. 14) and the main furnace housing may be moved up and around as described above. A warning device, generally indicated by reference numeral 140 is provided to prevent the breaking of the pressure seal between the main furnace housing 15 and furnace base 16 before the furnace has been depressurized. This warning device 140, shown in cross section in FIG. 12, comprises a right-angled metal sheet piece, one leg 141 of which is bolted to the upper surfaces of the enlarged ends 122 and 123 of the sealing ring and the other leg 142 of which extends upwardly along the side of the furnace housing 15 slipping over an apertured threaded screw 143 screwed into the side of the furnace housing and sealed around its periphery to make a fluid-tight seal with the furnace housing. The apertured screw is sealed at its end with a cap 144, which has a plurality of radial passages 145, and a gasket 146. The cap abuts leg 142 of the metal piece. In order to unbolt the sealing rings, it is necessary to

unbolt the leg 141 of the metal piece from the two enlarged ends of the semi-circular rings thereby breaking the seal of gasket 146. If the interior of the furnace is still pressurized when this is attempted, the high pressure gas escaping through the aperture in screw 143 and one or more of the radial passages 145 will emit a high-pitched warning signal to the operator.

Gas for pressurizing and purging the working volume within the furnace is introduced through duplicate gas inlet lines 151 and 152 (FIG. 11). The gas flow is controlled by a valve, e.g., valve 153, associated with each of the inlet lines. The lines are located in the viewing window housing, positioned to cause the gas jet to impinge on the internal surfaces of the windows in the viewing ports as described more fully in connection with FIG. 14.

Either of the viewing ports may have a TV camera mounted on it. In FIG. 11, the TV camera mount 24 is affixed to viewing port 22 through a mount support 155 affixed to an adjustable collar 156 which fits around the viewing port. The position angle of the TV camera may be adjusted by moving camera plate 157 through the turning of screw 158. A liquid coolant is introduced into and withdrawn from the cooling passages of the crystal pulling rod through inlet line 160 and discharge line 161 as described in detail with reference to FIG. 19.

Although the crucible containing the molten material from which the crystal is pulled may or may not be moved during the crystal pulling operation, it is necessary to be able to move the crucible-support rod through a short excursion, e.g., 2 inches or so to be able to adjust the support for different sized crucibles. The crucible support rod may also be rotated during positioning and crystal formation if desired. Crucible-support rod driving means 20 (FIGS. 10 and 13) therefore includes a translational (vertical) drive motor 165 with shaft 166 (comparable to motor 51 and shaft 76 of the crystal-pulling drive mechanism); and a rotational drive motor 167 with shaft 168 (comparable to motor 58 and shaft 62 of the crystal-pulling drive mechanism). These motors are affixed to crucible-support rod housing 169 through plate 170. The crucible-support rod housing is in turn suspended directly under the furnace base 16 through a support assembly 171 affixed to base plate 40. Temperature at the bottom of the crucible is monitored by a thermocouple, the wires 171 of which are shown extending out from crucible-support rod housing 37.

The furnace lifting shaft 96 extends through base plate 40 below which it is connected to the main drive piston 175 of hydraulic drive mechanism 176 through connecting shaft 177 and two universal joints 178 and 179. The hydraulic fluid is pumped in and out of the hydraulic drive mechanism 176 through conduit 180 by pump 181 driven by motor 182, the pump and motor being mounted in frame 41. The pump controls (not shown) are located on the furnace unit.

The pressure control means 187 for maintaining the desired pressure (from 10^{-5} torr to 135 atmospheres) is located below base plate 40 and is shown in FIGS. 10 and 13. The working chamber defined within the furnace is evacuated through gas discharge line 188 (communicating with the gas discharge port shown in FIG. 14), valve 189 and vacuum line 190 which communicates with a vacuum pump, not shown. Valve 189 has a manually operable handle 191 permitting the closing

off of the furnace chamber from the vacuum system and making possible the remote control of gas vent line 192 through which pressurizing gas may be controllably vented from the furnace by way of one of two control means and line 193 (FIG. 10). Venting of the gas through line 192 is effected through a manually controlled valve 199 located on the operational control console 12 (FIG. 1) or by an electrical solenoid valve 195, the switch for which is also on the control console. Associated with the pressure control means 187 is also a pressure relief valve 194 set to open at a predetermined maximum temperature. Pressurizing gas, introduced through lines 151 and 152 (FIG. 11) is supplied from a suitable source, not shown, and the control of gas flow into the furnace is effected through the valves (e.g., valve 153 of FIG. 11) associated with lines 152 and 152.

The power inlet conduit 30 is mounted in frame 41. The power leads, one of which is shown at 196, are supported in insulating rings 197 within conduit 30 and are extended upwardly through conduits 198 which pass through base plate 40 and through furnace base 16 into the furnace chamber as illustrated in FIG. 14.

FIG. 14 shows the furnace in cross section and illustrates one embodiment of the crucible holding assembly as well as the use of rf coils as the crucible heater. The main furnace housing 15 is formed of a lower section 205 with a flange 206, a main central section 207 and a top section 208 having a central opening 209 adapted to receive the crystal-pulling rod bearing and sealing assembly described in connection with FIG. 17. These sections of the main furnace housing are welded together. The furnace base 16 comprises a shallow, bowl-shaped member 210 having a flange 211, matching flange 206 of lower section 205 of the main furnace housing, and a bottom section 212 having a central opening 213 adapted to receive the crucible-support rod bearing and sealing assembly identical for that for the crystal-pulling rod shown in FIG. 17. An o-ring seal 214, recessed in flange 211, is provided to effect the seal between flanges 206 and 211. FIG. 14 illustrates the internally grooved structure of the two semi-circular rings 120 and 121 of the furnace closure means.

Within the furnace housing is a working chamber 220 in which the crucible assembly 26 is positioned. The extended volume above the crucible assembly permits the drawing of a long crystal 14 by the upward movement of crystal-pulling rod 222 from a molten pool 223 contained within a crucible 224. The crucible 224 may be formed of a variety of known materials in a variety of configurations. The crucible is set within a crucible-support assembly which in turn is supported on crucible-support rod 225, the construction of which and the sealing and bushing assembly for which is described more fully in connection with the description of FIGS. 15 and 17. The crucible-support assembly, which is interchangeable, is shown in the embodiment of FIG. 14 to comprise an interchangeable outer quartz shielding 230 which is set in a collar 231 adapted to rest on the upper lip of central opening 213; and a crucible holder support collar 232 fitted around rod 225 and configured to hold the downwardly extending neck 233 of the crucible holder 234. The crucible-support rod 225 extends into crucible holder support 232 which has an internal shoulder to engage the outer upper rim of crucible-support rod 225. An axial passage 235 extends

through neck 233 providing for the location of thermocouple junction 236 of wires 171 near the bottom of crucible 224. A radiation shield 237 is mounted between the bottom of crucible holder 233 and the shoulder of the quartz shielding 230. Normally the crucible holder 234 will be formed of graphite to enable it to serve the dual role of holder and rf susceptor. If the molten material 223 is of a character that can be contained within graphite, then the crucible holder may also serve as the crucible. Boron nitride may be cited as an exemplary material from which the crucible holder support 232 may be formed.

The crucible and its contents are shown to be heated by an rf coil 240 having leads 241 and 242. Each of these leads terminates in the upper half of a separable electrical lead connector. FIG. 14 illustrates the connector 243 and rf feed-through only for lead 241, it being understood that there is an identical arrangement for lead 242. Thus lead 241 terminates in the upper half 244 of connector 243 which has a fixed lower half 245 thus making it possible to readily engage and disengage lead 240 and to interchange the rf coil. The lower half 245 of connector 243 is connected to rf lead 196 sheathed in conduit 198 (See also FIG. 13) which extends through a Conax-type, Teflon sealed feed tube 246 terminating in opening 247 drilled in the bottom section 212 of the furnace base. A sleeve 248 is fitted into opening 247, and it serves as a support for a skirted plug 249 fitted around lead 196. This arrangement provides for a fluid passage, between opening 247 and working chamber 220, comprising the interior of sleeve 248, annular passage 250, openings 251, in sleeve 248 and annular passage 252. This fluid passage permits the venting of this cavity to the working chamber; and at the same time it provides a water and dust cover for the feed through tube 246 when the interior of the base of the furnace is exposed.

The gas discharge line 188 (FIGS. 10 and 13) communicates with furnace working volume 220 through a pumping port formed of another sealed feed-through 255 mounted in an opening 256 in bottom section 212. A sleeve 257 is fitted into opening 256 and is covered with cap 258 held in spaced relationship from sleeve 257 by means of a plurality of tabs 259, an arrangement which provides fluid communication between working volume 220 and gas discharge line 188 and a dust cover over the line.

Only one of the viewing ports is shown in cross section in FIG. 14. The other viewing port 21 is, however, identical to viewing port 22 and need not be described. Each of the viewing ports is positioned and aligned to permit a relatively wide view of the crystal growing area within furnace volume 220. Each primary viewing port is formed of a main housing 265 which is welded to the central section 207 of the furnace housing, and of a window cap ring 266 which is affixed to the main housing by means of a plurality of screws one of which is shown at 267. The viewing port 268 is defined within the cap ring 266. The window housing and cap ring are so configured as to define between them a circular recess in which a tempered pyrex window 269 is held. The seal between the window surface and the main housing is made through an o-ring 270. The internal pressure load on window 269 is carried through elastomeric washer 271 to window cap ring 266. In order to protect the pyrex window and control the optical character of the image transmitted through it there is inter-

posed between window 269 and the crystal growing area an adjustable infrared-reflecting window 272 which serves to reduce the axial temperature gradient on window 269. This window 272 is held in an annular mounting ring 273 rotatable within the main housing 265 by virtue of the screw thread arrangement. A cross-polarizer 274 is rotatably mounted in frame 275 on the cap ring 266. Its purpose is to control the intensity of the image transmitted through window 269.

10 Gas for flushing out the furnace or for pressurizing it is introduced by way of a gas line 151 (FIGS. 11) which is so positioned as to cause the incoming gas to impinge upon the exposed surface of the infrared-reflecting window 272. This makes it possible to clean the window whenever necessary.

FIG. 15 shows how a smaller crucible may be accommodated by lengthening neck 233 of the crucible holder 234 and shaping the holder to fit the crucible. If rf heating is to be used, an appropriately sized coil 20 with appropriately designed leads can easily replace the larger coil 240 of FIG. 14 by engaging a coil connector with lower connector half 245. It will be appreciated by those skilled in the art that the crucible assembly may assume a number of different configurations and vary 25 widely in size.

It may, under some circumstances, be desirable to use resistance heating rather than rf heating. FIG. 15 shows one exemplary embodiment of resistance heating. The heating element is a graphite resistance heater 30 276 formed of two half-cylinder thin-walled sections 277 separated by two thin gaps (one being shown at 278), a thick-walled upper ring 279 providing a low-resistance path and two lower thick-walled half-rings 280. The graphite heater is mounted by means of bolts 35 281 through the half-rings to a water-cooled copper pad formed of two semicircular sections 282 spaced apart to continue gap 278. The heater is connected in a power circuit through separate connectors adapted to make electrical connections with the two sections of 40 the copper pad. In FIG. 15 only connector 283 associated with the copper pad section shown on the left side is illustrated. An identical connector is provided for the other pad section. Both power and cooling water are brought in through feed-through 246. In like manner a 45 feed-through (not shown) is associated with the other half of the graphite heater to provide the other electrical connection and to withdraw cooling water.

The copper pad is supported through a plurality of 50 electrically insulating stand-offs 284 on an annular platform 285 held by means (not shown) in the furnace base. A quartz shielding 286 surrounds the heating assembly and snaps into a ring cut in the copper pad sections. The molybdenum sheeting 287, wound around 55 with spacers (not shown) to form a plurality of spaced-apart cylindrical radiation shieldings, is hung by means of several elongated S-shaped hooks 288, affixed to the rim of quartz shielding 286, in the annular spacing 289 defined between the quartz shielding and the heater.

60 FIG. 15 also illustrates the bearing and sealing assembly for the crucible-support rod 225, the crucible-support rod drive mechanism 37, and the rod housing. The bearing and sealing assembly 292 is identical to that used for the crystal-pulling rod which is described 65 below in detail in connection with FIG. 17. Likewise, the crucible-support rod drive mechanism 37, the rod housing 293, and the rod clamp assembly 294 are iden-

tical to that used for the crystal-pulling rod described below, except that the excursion of travel for the crucible-support rod is much less than that for the crystal-pulling rod. The base of the furnace is cooled by circulating a liquid coolant, e.g., water, in an annular passage 295 supplied by an inlet conduit and withdrawn through a discharge conduit, as shown in FIG. 20.

FIGS. 16-18 illustrate in detail the mechanisms by which the crystal-pulling rod 222 is given rotational and translational motion and the manner in which this mechanism is connected to shaft 76 (FIG. 3). The mechanism illustrated in these figures is essentially the same as that which is disclosed in U.S. Pat. No. 3,552,931.

Turning first to FIG. 16 it will be seen that this drawing illustrates the main elements which make up the translation and rotational driving system associated with the crystal-pulling rod 222 and hence which are connected to shafts 76 and 62 (FIG. 4). The shaft 76 extending from the vertical driving mechanism illustrated in FIG. 4 is coupled to a driving worm 300 through a coupling 301 and a shaft attachment 302. The driving worm 300 in turn engages the translational driving means generally indicated by the number 303. It will be seen that this comprises a vertical driving screw 304 which terminates in a pulling rod clamp assembly 305 detailed in FIG. 19. As will be explained below the vertical drive screw does not itself rotate but experiences only translational motion. This in turn requires that the rotation be achieved by a rotary spur gear 307 attached to the lower pulling head shaft by clamp assembly 308 which is mounted on crystal-pulling rod 222 and which is in turn driven by rotary drive motor 58 through shaft 62 which terminates in a driving gear 310. This driving gear 310 in turn engages the driven gear 311 mounted on shaft 312 which has affixed to it a rotary drive pinion shaft 313.

The rod actuating assembly may now be described in detail with references to FIGS. 17, 18 and 19. It is the purpose of the crystal-pulling rod clamp assembly generally indicated by the number 305 and shown in detail in FIG. 19 to affix the crystal pulling rod 222 to the drive screw 314 so that the rod 222 may rotate within the drive screw 314 which does not itself rotate but which imparts only translational motion to the rod 222. This clamp assembly 305 comprises a thrust bearing 315 which is held in a thrust bearing housing 316 by means of a snap ring 317. A bushing 318 is provided at the upper end of the drive screw 314. The rod and clamp assembly are free to rotate in the bushing 318 and in the drive screw which experiences only translational motion.

Translational motion is imparted to the crystal-pulling rod 222 through the mechanism generally indicated by the numeral 303 (FIG. 17). In the achievement of the translational motion as explained above the drive screw assembly does not rotate. Rather, the threaded nut 319 which engages the threads of the vertical drive screw 314 rotates in the bushing 320 and this is accomplished by virtue of its connection, through a shoulder 321, to a worm wheel 322 which in turn is driven by the worm 300. This rotating assembly is mounted between an upper thrust washer 323 and a lower thrust washer 324 which is maintained in position through a thrust plate 325. Reference to FIG. 18 will show that this thrust plate 325 is attached through shoulder screws 326 to the casting which forms the

housing 327, enclosing the driving mechanism. Through this attachment tension loads on the crystal-pulling rod 222 are transmitted to the casting through screws 326.

5 Returning to FIG. 17 it will be seen that the bottom end of the drive screw 314 is affixed to an anti-rotate plate 328 which in turn is affixed to the anti-rotate arm 329 engaging the anti-rotate shaft 330. At the bottom terminus of the drive screw there is a bushing 331 in 10 which the rod 222 rotates. The spur gear 307 for rotating the rod is mounted on the shaft through clamp 308, a pin 332 and a thrust bearing 333 held in place by means of a snap ring 334.

The worm drive adapter assembly 335 for translational motion is shown in the cross section of FIG. 18. 15 The worm 300 is affixed to worm shaft 336 which is mounted in the main housing 327 through a forward shaft mount 337 and a flanged bushing 338, and an after shaft mount 339 (attached to the back plate 340 20 of the housing) and a flanged bushing 341. The shaft 336 has an extension 302 adapted for attachment to the shaft 76 (see FIG. 16) and the mount 339 has a threaded section 342 which is adapted for attachment through threaded collar 301 (FIG. 16) for making the 25 proper connection with the shaft casing.

The rotary drive adapter assembly is also shown in detail in the cross section of FIG. 18. It is generally indicated by the numeral 343. The driving bevel gear 310 is mounted a shaft 344 which is retained in a shaft 30 mount 345 fixed to the back plate 340 of housing 327. A forward flanged bushing 346 and an after flanged bushing 347 are provided for the shaft 344. A suitable adapter piece 348 is attached to the end of the shaft and is designed to join shaft 344 with shaft 62 (FIG. 16) 35 which is associated with the rotary drive motor 58 (FIG. 4). Finally, it will be seen that the housing has in addition to the back plate 340 a removable front plate 349 which completes the housing.

The crystal-pulling rod mechanism 55 of FIG. 17 is 40 attached to the top section 208 of the main furnace housing through a plurality of screws, the engaging threaded opening for one of which being shown as 351 in FIG. 14.

FIG. 17 also illustrates in detail the manner which a 45 pressure seal is effected around rod 222 as it experiences translational and rotational motions. The bushing housing, which fits into opening 209 of the upper furnace, shown generally as numeral 352, will be seen to comprise an adapter piece 353 in which there is located a bushing 354 furnishing the necessary alignment for the rod 222 as it extends beyond the top of housing 327. The adapter piece 353 is arranged to be connected with the upper section 208 of the furnace housing 50 of FIG. 14. For this purpose there is provided an annular groove 355 which is suitable for retaining an o-ring 356.

The adapter piece 353 contains a gland seal generally 55 indicated by the numeral 357. This seal comprises a body piece 358, an o-ring 359 which contacts the surface of rod 222, an o-ring 360 which seals the gland body to the adapter piece 353, a felt wiper 361, and a metallic wiper ring 362. The gland assembly is threaded into adapter piece 353 and the wipers are held in place by a snap ring 363. The end of the gland body terminates in a hexagonal member 364. When the pulling head assembly is attached to the main furnace housing 15 a fluid-tight seal with inner volume 220 is achieved

through o-ring seals 356 and 360. The crystal-pulling rod must, of course, rotate and move while retaining this fluid-tight condition within the furnace and the o-ring seal 359 makes this possible. The gland assembly is designed to resist the pressure of the friction forces which must be easily and quickly removable for cleaning or replacement of o-rings.

The rotary drive pinion 313 and its associated shaft 312 are retained in position within the housing and mounted therein through a flanged bushing 365 which is positioned within a section 366 of the housing top. A fine pitch adjustment screw 367 and a suitable set screw 368 are provided for axial adjustment of the pinion shaft in order to obtain proper bearing clearances. An electrical connection opening (not shown) is provided in the housing for passing through the necessary electrical lines for travel-limiting microswitches as shown generally at 369. The microswitches 369 (both upper and lower) are actuated by anti-rotate arm 330. The upper portion of the crystal-pulling rod 222 extends into a dust cover 370 which is affixed to the housing 327 through collar 371.

The sealing and bearing assembly 290 (FIG. 15) associated with crucible-supporting rod 225 is identical to that gland seal 252 associated with the crystal-pulling rod 222. In FIG. 15 like reference numerals are used to identify like components in the sealing and bearing assembly as well as in the rod driving mechanisms for the crystal-pulling and crucible-support rods.

The crystal-pulling rod 222 is constructed to be cooled, and it therefore incorporates means to inject and withdraw a liquid coolant, e.g., water. FIG. 19 shows the uppermost section of the crystal-pulling rod 222 in detail as well as the means for cooling the rod. The dust cover 370 affixed to main shaft housing 327 is closed with a metallic cap 372 which snaps down over its top and provides the housing for the crystal-pulling rod 222. In order to cool the rod 222 it is necessary to be able to direct a fluid coolant down through the rod and then return it for discharge. To do this, there is provided a gland body 375 surrounding the upper portion of the rod and tightly sealed thereto through an upper o-ring 376, a weld 377 and a lower o-ring 378. The gland body 375 is affixed to the drive screw 314 over a neck position 379 of the drive screw. The rod itself is formed of an outer tubing 380 and an inner tubing 381, the latter having internal thereof an inner coolant passage 382. The outer tubing 380 and the inner tubing 381 define between them an annular outer coolant passage 383. The passage 383 is closed at the terminal end of the inner tubing 381 by means of a suitable plug 384. Above the plug 384 and defined within the outer tubing 380 is an inlet coolant chamber 385 which is in fluid communication with an upper annular groove 386 defining a fluid passage and connected to the chamber by means of a series of ports 387. The annular passage 386 in turn is in fluid communication with inlet conduit 388 which is in turn, through a suitable coupling, connected to an inlet water tubing 160 (FIG. 11) terminating in a quick disconnect 393. At the bottom end of the cooled rod 222 there is placed a solid plug 394 which in effect closes both the inner coolant passage 382 and the outer coolant passage 383. Communication between these two is through ports 395.

In operation water or other coolant is introduced through tubing 160 and passes by way of chamber 385

into the inner water passage defined by the inner tubing 381. At the end of the rod the cooling water is transferred through ports 395 into the outer water passage 383 and returned via this passage, ports 390, annular passage 391, and conduit 392 into outlet tubing 161. As the rod 222 is moved up and down the inlet and outlet conduits 388 and 392 move within the elongated opening 396 in dust cover 373.

As indicated in FIG. 1, a cooling system 44 is provided for the furnace housing and viewing ports. This cooling system comprises a coil system for circulating a suitable coolant such as water. This coil system is shown diagrammatically in FIG. 20. In the system cooling coils are wrapped in heat exchange relationship to the outside walls of the furnace components. Thus coil 400 is associated with the central furnace section 207, coil 401 with viewing port 21, coil 402 with viewing port 22, coil 403 with the lower furnace section 205, and coil 404 with the furnace base 16. As will be seen in FIG. 20, the coils are two fluid conduits wound in parallel as indicated by the solid and dotted lines. These are joined by a loop 405 which has two valve-controlled connections 406 and 407. The coolant may be introduced into one side of the parallel coils such as by a suitable line (not shown) joined through connection 408 and withdrawn through the other side of the coils such as by a suitable line (not shown) joined through connection 409. Alternatively, some or all of the coolant may be withdrawn through a line attached to connection 406 and fresh or additional coolant added through a line attached to connection 407. This alternative arrangement provides flexibility in the manner in which the furnace assembly may be cooled. As shown in FIG. 15, the bottom of the furnace is also cooled by circulating a liquid coolant in the annular passage 295 by introducing it into line 296 and withdrawing it through line 297, connections between these lines and passage 295 being made through 298. An identical cooling arrangement is used for the top of the furnace housing.

In operating the furnace it is very desirable for the operator to know at all times the precise position of the crystal-pulling rod. A continuous rod-position readout system is therefore associated with crystal-pulling rod 222 as shown in FIG. 21. This readout system is integrated into the vertical drive system of FIG. 16 and like numerals are used to identify like components in FIGS. 16 and 21. Extending beyond the vertical drive worm 300 and affixed thereto is a shaft 410 which has a magnet 411 attached at its end and along one side of it. The shaft 410 and its magnet rotates in a switch system 412 having a magnetic reed switch 413 positioned on one side of the shaft. The magnetic reed switch is electrically connected to the central terminal of portion 414 of a wafer switch (having another portion 415) and to a reversible electromagnetic counter 416 set to record the distance traveled by the rod 222 from its bottom-most position in hundredths of inches. The connections between the reversible counter and the DC motor control 417 and the wafer switch 414/415 are such as to register the addition of shaft 410 turns as crystal pulling rod 222 moves upwardly and to register the subtraction of shaft 410 turns as rod 222 moves downwardly. Thus the counter always records the precise position of the rod no matter in which direction the rod moves. This precise position is made possible by the worm gear

ratio and thread pitch such that rod 222 moves 1 inch while shaft 410 turns 100 revolutions.

It is also, of course, within the scope of this invention to increase the sensitivity of the position determining device by increasing the number of magnets mounted on shafts 410 as well as to adapt the device to register in metric units.

In crystal growing, precise temperature control of the crystal forming melt in the crucible 224 (FIG. 14) is necessary. This may be done automatically by the mechanism diagrammed in FIG. 22. A light pipe 420, may be positioned to extend between the rf coil to within very close proximity of the surface of the graphite crucible holder 233 (FIG. 14) and connected to a radiamatic pyrometer 421 which in turn is connected to a proportional temperature control system 422 such as a Leeds and Northrup HAZAR recorder or CAT Electric controller, which processes the d.c. signals received and transmits them, via a magnetic amplifier 423, in the form of an amplified signal to a saturable core reactor 424 which controls the amount of current transmitted to the induction heating power supply 425. Thus, by setting the temperature control system 422 at the desired temperature the amount of power delivered to the rf coil 240 is controlled and the temperature is maintained at the desired level. A pyrometer 426 may be connected to thermocouple junction 236 which gives a direct reading of temperature to the operator. FIG. 23 illustrates in diagrammatic fashion the mechanisms which control the speed and direction of the rotational and translational motions of the crystal-pulling and crucible-support rods 222 and 225. In the description of FIG. 23 reference should also be had to FIGS. 3-5 which illustrates the drive trains. In FIG. 23, like reference numerals are used to identify like components identified in preceding figures. The DC motor control 417 serves as the means for controlling the direction and rate at which crystal-pulling rod 222 is moved; while the DC motor control 430 serves as the means for controlling the direction and rate at which crucible-support rod 225 is moved. In similar fashion, DC motor control 431 is associated with the crystal-pulling rod rotational drive motor 58 and motor control 432 with the crucible-support rod rotational drive motor 167. The travel-limiting microswitches 369 are connected to the appropriate motor controls as shown. A single DC clutch power supply 433 is connected to low-speed clutch 69 and high-speed clutch 88 through a single-pole double-throw switch 434, the controls 435 of which are located on the console 12. It will be understood that all of the controls on console 12 have not been identified for their positioning and construction are within the skill of the art and they need not be further identified.

From the above description it will be seen that the furnace assembly of this invention provides an apparatus suitable for large-scale, commercial production of crystals through the use of the Czochralski technique. Because of the wide ranges of pressure and temperature available to the

from a wide variety of materials, including those such as the arsenides and phosphides which normally present serious problems because of their high volatility.

It will thus be seen that the objects set forth above, among those made apparent from the preceding description, are efficiently attained and, since certain changes may be made in the above constructions with-

out departing from the scope of the invention, it is intended that all matter contained in the above description or shown in the accompanying drawings shall be interpreted as illustrative and not in a limiting sense.

We claim:

1. A pressure- and temperature-controlled apparatus adapted for growing crystals by the Czochralski technique, comprising in combination

- a. pressure-tight furnace means providing an enclosure defining therein a working volume the atmosphere of which may be varied with respect to temperature and to pressure from a vacuum to at least 100 atmospheres, said furnace means being formed of a main cylindrical furnace housing of essentially constant diameter throughout having a top section and bottom flange means and a furnace base member having the same inside diameter as said main furnace housing and being sealable with said main furnace housing through mating flange means to limit said atmosphere essentially to said volume;
- b. furnace sealing means engageable with said mating flange means and comprising two semicircular, internally grooved members and bolt means adapted to lock said grooved members in engaged position around said mating flange means;
- c. crystal-pulling rod means extending from external of said main furnace housing into said volume and movable therein in both rotational and translational modes;
- d. crystal-pulling rod bearing and sealing assembly means located in said top section of said main furnace housing and providing the sole sealing means between said crystal-pulling rod means and said pressure-tight furnace means;
- e. rotational and translation crystal-pulling rod driving means located external of said pressure-tight furnace means and rigidly mounted on said main furnace housing, said translational driving means including means to selectively drive said rods in a slow crystal-growing mode or in a rapid-positioning mode;
- f. main furnace housing support and lifting means to which said main furnace housing is affixed, said support and lifting means being adapted to raise said main furnace housing, said crystal-pulling rod means and said crystal-pulling rod driving means as a single rigid assembly off said furnace base member and to permit said single rigid assembly to be swung around when it reaches a predetermined height;
- g. crucible-support rod means extending from external of said furnace base member into said volume above said furnace base member and movable therein in both rotational and translational modes;
- h. crucible-support rod bearing and sealing assembly means located in said furnace base member and providing the sole sealing means between said crucible-support rod means and said pressure-tight furnace means;
- i. rotational and translational crucible-support rod driving means located external of said pressure-tight furnace;
- j. rod-locating means associated with said translational driving means of said crystal-pulling rod means adapted continuously to indicate at a location remote from said furnace means the precise

- position of said crystal-pulling rod means within said volume;
- k. crucible holding means supported on said crucible-support rod means and positioned above the upper level of said base means;
- l. heating means adapted to heat the contents of a crucible held within said crucible holding means; and
- m. viewing port means providing for visual observation of said working volume.
2. An apparatus according to claim 1 wherein said pressure-tight furnace means includes external cooling means in the form of coils adapted to circulate a fluid coolant.
3. An apparatus according to claim 1 wherein said pressure-tight furnace means has associated therewith a self-resetting pressure-relief valve and a solenoid-actuated relief valve.
4. An apparatus according to claim 1 wherein said pressure-tight furnace means includes audible pressure warning means associated with and actuated by said furnace sealing means.
5. An apparatus according to claim 1 wherein said crystal-pulling rod means incorporates fluid channels therein adapted to circulate a fluid coolant therethrough.
6. An apparatus according to claim 1 wherein said crucible-support rod means provides a passage for thermocouple lead wires extending into said crucible holding means.
7. An apparatus according to claim 1 wherein said main furnace housing support and lifting means com-

- prises a hydraulically operated lifting shaft attached to said main furnace housing and means to prevent the rotation of said shaft until it reaches said predetermined height.
- 5 8. An apparatus according to claim 1 wherein said crucible holding means comprises a crucible holder terminating at its lower end in a neck member adapted for attachment through a collar member to said crucible-support rod, and outer shielding means surrounding said crucible holder, said crucible holder and said outer shielding means being readily interchangeable, thereby providing means to hold crucibles of varying sizes and configurations.
- 10 9. An apparatus according to claim 1 wherein said heating means comprise rf coil means surrounding said crucible holding means.
- 15 10. An apparatus according to claim 1 wherein said heating means comprise resistance heater means surrounding said crucible holding means.
- 20 11. An apparatus according to claim 10 wherein said resistance heater means comprises a graphite resistance heater, a copper pad, means to circulate a liquid coolant in said copper pad, and means to support said heater means.
- 25 12. An apparatus according to claim 1 wherein said heating means has leads terminating in connecting means engageable with connecting means positioned within said furnace base member, whereby said heating means may be readily interchanged to accommodate different sized crucibles.
